COMBINED BLOUSE AND SLIP

Leea M. Perlitch, New York, N. Y.

Application July 23, 1941, Serial No. 403,599

2 Claims.

(Cl. 2-74)

This invention relates to new and useful improvements in a combined blouse and slip.

The invention proposes a combination infant's, child's and junior's blouse and slip connected together as a unit so that the slip will hold the blouse down and overcome an inconvenience of standard blouses which ride up out of the skirt, and the blouse in turn will effectively support the slip and avoid the annoyance of a sagging slip, and the requirement of wearing a separate slip and blouse.

In accordance with this invention the blouse may be of any design and construction, and may have sleeves or be sleeveless, and may be of any size. Similarly, the slip may be of a desirable length and design.

Still further the invention contemplates characterising the blouse and slip by the fact that these parts are sewn or connected together as a unit.

Still further the invention proposes the provision of buttons, or other supporting elements mounted upon the blouse for assisting in supporting a skirt or similar garment over the slip. An arrangement is also proposed for properly supporting the slip so that it will not show from the bottom of the skirt.

Another object of the invention is the construction of an article as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front elevational view of a combined blouse and slip constructed in accordance with this invention.

Fig. 2 is a fragmentary enlarged vertical sectional view taken on the line 2-2 of Fig. 1.

Fig. 3 is a front elevational view of a combined blouse and slip constructed in accordance with another embodiment of this invention.

Fig. 4 is a fragmentary enlarged vertical sectional view taken on the line 4-4 of Fig. 3.

Fig. 5 is a sectional view similar to Fig. 4 but showing the parts in a different position.

Fig. 6 is another view similar to Fig. 1, but illustrating a still further modification of the invention.

Fig. 7 is a fragmentary enlarged sectional view taken on the line 7-7 of Fig. 6.

In the form of the invention illustrated in Figs. 1 and 2, the combined blouse and slip includes a blouse 10 of any design, construction and size, to the bottom edge of which a slip 11

is secured by a line of stitches 12. The slip 11 may be of any desirable material and be of any size.

In the form of the invention illustrated in Figs. 5 to 5 inclusive, the combined blouse and slip includes a blouse 15 of any design, shape and size connected with a slip 16. A line of stitches 19 is utilized to secure together the adjacent portions of the blouse and slip.

Several buttons or other fastening elements 17 are mounted upon the bottom portion of the blouse 15 and are adapted to assist in supporting an outer skirt. The slip 16 is also provided with several vertical lines of buttonholes 18 which may be selectively engaged upon the buttons 17, as illustrated for example in Fig. 5, to shorten the slip and prevent it from projecting beneath one's outer skirt.

In Figs. 6 and 7 the blouse 15' is illustrated with a bottom projection 15^a to form an overblouse effect when stitched to the slip 11' by stitches 19. In this form of the invention, the buttons 17' are provided at the inner side of the blouse 15' for selective engagement with the buttonholes 18' for the purpose of adjusting the slip with relation to the outer skirt.

With this combination garment any number of buttons may be added for attachment of the outer skirt. The blouse may also be joined to the slip by an elastic connecting band to give the blouse fullness, or by arranging a belt effect with loops on the blouse portion of the garment.

An important feature of the invention resides in the fact that the blouse will not slip out of an outer skirt. The garment will be exceptionally comfortable when worn. It is easy to launder, and moreover, is less expensive, than a separate blouse and a separate slip.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A garment having a blouse with its bottom edge attached to the top edge of a slip at the waist by a line of stitches, a row of buttons mounted on the bottom portion of said blouse above said line of stitches, and said slip being formed with a plurality of horizontal rows of vertically spaced button holes adapted to be selectively engaged with said buttons for lifting the bottom edge of said slip relative to said line of stitches, said slip having its top edge attached to the inside face of said blouse slightly inwards of its bottom edge forming a free bottom projec-

tion on said blouse which projects downwards over the outside face of said slip.

2. A garment having a blouse with its bottom edge attached to the top edge of a slip at the waist by a line of stitches, a row of buttons mounted on the bottom portion of said blouse above said line of stitches, and said slip being formed with a plurality of horizontal rows of vertically spaced button holes adapted to be se-

lectively engaged with said buttons for lifting the bottom edge of said slip relative to said line of stitches, said slip having its top edge attached to the inside face of said blouse slightly inwards of its bottom edge forming a free bottom projection on said blouse which projects downwards over the outside face of said slip, said buttons being mounted on the inside face of said blouse.
